FIG. 1

FIG. 2

FIG. 3

FIG. 4

1
ADJUSTABLE STOOL

**CROSS REFERENCE TO RELATED
APPLICATION**

This application claims the benefit of the priority of U.S. Provisional Application No. 62/841,559 filed on May 1, 2019, the contents of these applications are hereby incorporated by reference in their entirety.

BACKGROUND OF THE INVENTION

The present invention is directed to an adjustable stool and more particularly an adjustable stool having a lumbar support.

Stools are well-known in the art for use at bars and the like. Most stools have fixed dimensions based upon the average height of individuals. While useful, conventional stools can be uncomfortable for individuals who are short or tall. Further, most stools provide little if any lumbar support and for those that do, the support is not properly positioned. Therefore, a need exists in the art for a device that addresses these deficiencies.

An objective of the present invention is to provide a stool that is adjustable for both tall and short people.

Another objective of the present invention is to provide a stool having an adjustable lumbar support.

These and other objectives will be apparent to those having ordinary skill in the art based on the following written description, drawings and claims.

SUMMARY OF THE INVENTION

An adjustable stool having a base with a support that extends vertically from the base. A foot rest is adjustably connected to the support. Attached to an end of the support opposite the base is a seat.

Adjustably attached to the seat is a back support that is adjustable in a horizontal direction in relation to the seat. A lumbar support is adjustably connected to the back support and is adjustable in a vertical direction in relation to the seat.

BRIEF DESCRIPTION OF THE DRAWINGS

FIG. 1 is a side view of an adjustable stool;
FIG. 2 is a perspective view of an adjustable stool;
FIG. 3 is a perspective view of an adjustable stool; and
FIG. 4 is a side sectional view of an adjustable stool.

**DETAILED DESCRIPTION OF THE
PREFERRED EMBODIMENTS**

Referring to the Figures, an adjustable stool 10 includes a base 12. The base 12 is of any size, shape, and structure. In one example shown, the base 12 has an outer edge 14 and side walls 16 that angle inwardly to a top wall 18. Extending vertically through the top wall 18 of the base 12 is at least one vertical support 20. The vertical support 20 is of any size, shape, and structure and in one example, as shown, is a rectangular tube.

Adjustably connected to the vertical support 20 is a foot rest 22. The foot rest 22 is of any size, shape, and structure. Generally, the foot rest 22 has a foot engaging portion 24 connected to an adjustable portion 26. The adjustable portion 26 is of any form. In one example, the adjustable portion 26 is a horizontal bar adapted to be selectively received

2

within horizontal notches or grooves 28 that are vertically spaced on a back side of the vertical support 20.

In another example, the adjustable portion 26 includes a pair of vertical plates 30 having a centralized vertical slot 32. The vertical slot 32 aligns with a vertical slot 34 in the vertical support 20. A bolt 36 extends through slots 32 and 34 and is received within a tightening nut 38. The tightening nut 38 is rotated on the bolt 36 to engage a plate 30 and hold the foot rest 22 in a selected position.

In yet another embodiment, the adjustable portion 26 has a bracket 40 that fits about the vertical support 20. The bracket 40 has a hole 42. The hole 42 is positioned to selectively align with holes 44 in the vertical support 20 that are vertically spaced. The holes 42 and 44 are adapted to receive a locking pin 46.

Connected to a top end of the vertical support 20 is a seat 48. Adjacent the back 50 of the seat 48 is a back support 52. The back support member 52 has a horizontal portion 54 and a vertical portion 56 that form an L-shape. Both the horizontal 54 and vertical 56 portions have elongated slots 58. The horizontal portion 54 is connected to a bottom 60 of the seat 48 and is aligned with a cut-out section 62 on the back 50 of the seat 48. Bolts 36 are slidably received within slots 58 of the horizontal 54 and vertical 56 portions and are connected to a tightening nut 38.

One of the bolts 36 is connected to a lumbar support 64. The lumbar support 64 is of any size, shape, and structure. In the example shown, the lumbar support 64 is cylindrical.

In operation the stool 10 is adjustable in three ways to accommodate the differing heights of an individual, as well as provide proper support for an individual's lumbar. First, the foot rest 22 is adjusted to provide a comfortable distance between the seat 48 and the foot rest 22 similar to the distance between an individual's knee and foot.

Second, the back support member 52 is adjusted horizontally toward and away from the seat 48. In one example, the tightening nut 38 is loosened and the back support member 52 is moved toward or away from the seat to a distance similar to the distance between an individual's knee and spine. Once positioned, the tightening nut 38 is tightened to lock the back support 52 in the selected position.

Finally, the lumbar support 64 is adjusted vertically up or down along the vertical portion 56 of the back support 52. In one example, the tightening nut 38 is loosened and the lumbar support 64 moved to a position that aligns with an individual's lumbar. Once positioned, the tightening nut 38 is then tightened to lock the lumbar support 64 in the selected position.

Accordingly, an adjustable stool 10 has been disclosed that is adjustable to accommodate individuals of different height that also supports an individual's lumbar.

From the above discussion and accompanying figures and claims it will be appreciated that the stool 10 offers many advantages over the prior art. It will be appreciated further by those skilled in the art that other various modifications could be made to the device without parting from the spirit and scope of this invention. All such modifications and changes fall within the scope of the claims and are intended to be covered thereby. It should be understood that the examples and embodiments described herein are for illustrative purposes only and that various modifications or changes in the light thereof will be suggested to persons skilled in the art and are to be included in the spirit and purview of this application.

What is claimed is:

1. An adjustable stool, comprising:
a base;
a support extending vertically from the base;
a foot rest adjustably attached to the support;
a seat attached to an end of the support opposite the base;
a back support adjustably connected to the seat;
the back support having a horizontal portion and a vertical portion, wherein the horizontal portion has a first elongated slot and the vertical portion has a second elongated slot; and
10 a lumbar support adjustably connected to the back support;
wherein a horizontal portion of the back support aligns with a cut-out section on a back of the seat.
2. The stool of claim 1 wherein the back support is adjustable in a horizontal direction in relation to the seat.
3. The stool of claim 1 wherein the lumbar support is adjustable in a vertical direction in relation to the seat.
4. The stool of claim 1 wherein the foot rest is adjustable in a vertical direction in relation to the base.
5. The stool of claim 1 wherein the foot rest has a foot engaging portion and an adjustable portion.
6. The stool of claim 1 wherein the foot rest has an adjustable portion that is a horizontal bar that is selectively received in one of a plurality of notches vertically spaced on a back side of the support.
7. The stool of claim 1 wherein the foot rest has an adjustable portion, wherein the adjustable portion comprises a pair of vertical plates each having a centralize vertical slot that receives a bolt.
8. The stool of claim 1 wherein the foot rest has an adjustable portion, wherein the adjustable portion comprises a bracket that fits about the vertical support, and the bracket having a hole that selectively aligns with one of a plurality of holes vertically spaced on the support and the hole receives a locking pin.
9. The stool of claim 1 further comprising a first bolt slidably received within the first slot of the horizontal portion and connected to the seat such that the distance between the vertical portion and the seat is adjustable.
10. The stool of claim 1 further comprising a second bolt slidably received within the second slot of the vertical portion and connected to the lumbar support such that the distance between the horizontal portion and the lumbar support is adjustable.

11. An adjustable stool, comprising:
a base;
a support extending vertically from the base;
a foot rest adjustably attached to the support;
a seat attached to an end of the support opposite the base;
a back support adjustably connected to the seat;
the back support having a horizontal portion and a vertical portion, wherein the horizontal portion has a first elongated slot and the vertical portion has a second elongated slot; and
15 a lumbar support adjustably connected to the back support;
wherein the foot rest has an adjustable portion that is a horizontal bar that is selectively received in one of a plurality of notches vertically spaced on a back side of the support.
12. The stool of claim 11 wherein the back support is adjustable in a horizontal direction in relation to the seat.
13. The stool of claim 11 wherein the lumbar support is adjustable in a vertical direction in relation to the seat.
14. The stool of claim 11 wherein the foot rest is adjustable in a vertical direction in relation to the base.
15. An adjustable stool, comprising:
a base;
a support extending vertically from the base;
a foot rest adjustably attached to the support;
a seat attached to an end of the support opposite the base;
a back support adjustably connected to the seat;
the back support having a horizontal portion and a vertical portion, wherein the horizontal portion has a first elongated slot and the vertical portion has a second elongated slot; and
20 a lumbar support adjustably connected to the back support;
wherein the foot rest has an adjustable portion, wherein the adjustable portion comprises a pair of vertical plates each having a centralize vertical slot that receives a bolt.
16. The stool of claim 15 wherein the back support is adjustable in a horizontal direction in relation to the seat.
17. The stool of claim 15 wherein the lumbar support is adjustable in a vertical direction in relation to the seat.
18. The stool of claim 15 wherein the foot rest is adjustable in a vertical direction in relation to the base.
